United States Patent Office.

WESSEL BRODHEAD, OF MEADVILLE, PENNSYLVANIA.

Letters Patent No. 76,884, dated April 21, 1868.

IMPROVEMENT IN CARPENTERS' GAUGES.

The Schedule referred to in these Letters Patent and making part of the same.

TO ALL WHOM IT MAY CONCERN:

Be it known that I, WESSEL BRODHEAD, of the city of Meadville, in the county of Crawford, and State of Pennsylvania, have invented an improved Mode of Making Joiners' Gauges, and fastening the same without the aid of wedge or screw, consisting of two pieces and a marker.

I make my gauges of the ordinary sizes in use.

The bar is made oval, elliptical, or cam-shaped, to slide in a corresponding hole in the head-piece, so that, by a slight twist of the bar in one direction, and the head-piece in the other, they are firmly fixed to each other at any point on the bar.

Figure 1 shows an oval or elliptical-shaped bar, A, fixed in a corresponding hole in the head-piece B.

Figures 2 and 3 show a cam or scroll-shaped bar in its corresponding hole; C C being the marker; the dotted and full lines showing about the distance the parts move upon each other in the act of tightening.

I construct my bars from long pieces, planed out with a proper tool, and afterward cut to the proper lengths. The head-pieces are first bored, and then, with a gouge to correspond with the form of the bars, fitted in a mortising-machine. With one stroke the hole is completed.

What I claim as my invention, and desire to secure by Letters Patent, is—

The bar A and the head-piece B, constructed and operated as and for the purpose set forth.
